DESIGN FOR A FOOTBALL

Roland E. Jary, Fort Worth, Tex.

Application April 20, 1934, Serial No. 51,475

Term of patent 3½ years

To all whom it may concern:

Be it known that I, ROLAND E. JARY, a citizen of the United States, residing at Fort Worth, in the county of Tarrant and State of Texas, have invented a new, original, and ornamental Design for a Football, of which the following is a specification, reference being had to the accompanying drawing, forming part thereof.

I claim:—

The ornamental design for a football as shown.

ROLAND E. JARY,
